UNITED STATES PATENT OFFICE.

SAMUEL ELDER, OF WASHINGTON, DISTRICT OF COLUMBIA, ASSIGNOR TO MIEHLE PRINTING PRESS & MANUFACTURING COMPANY, OF CHICAGO, ILLINOIS, A CORPORATION OF ILLINOIS.

ROLL CONTROL.

Application filed August 27, 1923. Serial No. 659,495.

To all whom it may concern:

Be it known that I, SAMUEL ELDER, a citizen of the United States, residing at Washington, in the District of Columbia, have invented certain new and useful Improvements in Roll Controls, of which the following is a specification.

This invention relates to a new and improved roll control for printing presses and more particularly to means for disconnecting the roll from its drive mechanism and for retaining it against rotation and in a desired rotary position.

With certain types of presses as, for example, the presses used in printing engraved notes or the like, it is desirable to operate the press for a short time when starting up work or at other times without taking off impressions from the plate. With presses of this type it is necessary to keep a very accurate account of every impression made in order to prevent unauthorized production of notes. This count is usually kept by means of automatic counting mechanism associated with the impression roll of the press. It is therefore desirable to provide means for operating the press without rotating this impression roll.

It is an object of the present invention to provide impression roll driving mechanism adapted for disconnection from the roll to permit operation of the press without rotating the roll.

It is a further object to provide means adapted to engage the roll and retain it against rotation in a desired rotary position.

Other and further objects will appear as the description proceeds.

I have illustrated a preferred embodiment of my invention in the accompanying drawings in which—

Figure 1 is a fragmentary cross section of an engraving press showing the impression roll and associated parts;

Figure 2 is a section taken on line 2—2 of Figure 1;

Figure 3 is a view of the upper portion of Figure 1 as seen from the right; and

Figure 4 is an enlarged view partly in section showing the roll disconnecting means.

Referring now to the drawings, the impression roll 11 is provided with the shaft

12 carried in supports 13 and 14. These supports are mounted upon the press table 15, the plate carrying board 16 moving under the roll between the guideways 17 and 18 formed in the bed of the table. The supporting roll 19 is journaled in the lower ends of the support members 13 and 14 and is provided with the gear 20 through which it is driven. Upon its opposite ends it is provided with gear 21 which by means of gears 22 and 23, shown in Figure 3, drives the gear 24 carried upon the outer end of the impression roll shaft 12.

As shown in Figure 2, the roll 11 is provided with a recess 25 in which the edges of the roll cover 26 are secured by clamp means 27. This recess forms a depressed portion on the roll surface so that when this portion of the roll is down, the surface of the roll does not contact with the plate 28 carried by the board 16.

The link 29 is pivoted to the support 14 upon stud 30. This link is provided with the notch 31 adapted to engage the pin 32 which projects from the end of the roll 11. This pin is so located that the link maintains the roll in position with its depressed portion opposite the press bed as shown in Figure 2. As shown in Figure 3, the support 14 is provided with the pin 33 which serves to limit the downward swinging movement of the link 29 when it is in its disengaged position.

The gear 24 is loosely fitted upon the reduced portion 34 of the shaft 12. The arm 35 is clamped by bolts 36 upon the outer reduced portion 37 of the shaft 12. This arm 35 is provided with a bore 38 in which is fitted the pin 39. This pin is provided with the slot 40 having notches 41 and 42 therein. The detent 43 is pressed by spring 44 into the recess and notches. The gear 24 is provided with a recess or opening 45 therein which is of a size to receive the end of the pin 39.

In the use of the press, when it is desired to operate the press mechanism without operating the impression roll, the pin 39 is drawn out to the dotted line position shown in Figure 4. This is permitted by the detent 43 pressing upwardly the spring 44. At the outer position the detent will drop in notch 41. These notches and the detent are so related as to permit inward or outward move-

ment when the pin is positively operated, but to prevent accidental movement. After the pin is withdrawn, the link 29 is swung in the counterclockwise direction as seen in Figure 3 until the notch 31 engages the pin 32 carried by the roll. It will be necessary, of course, for the roll to be in a position in which it is shown in Figure 2, which position is the normal one intermediate two impressions.

With the roll lock in this position, the press may be operated for any desired purpose, such as cleaning and oiling, without the impression roll rotating and without the possibility of any impressions being struck off from the plates. Consequently the counting mechanism associated with the roll need not be operated as there is no necessity of counting movements of the press which cannot produce impressions from the plates.

To again connect the roll to the driving mechanism, it is only necessary to bring the press to such position that the opening in the gear 24 coincides with the position of the pin 39 and to then thrust this pin into the opening 45. The link 29 is then un-

hooked from the pin 32 and swung back against the pin 33.

While the present invention has been described as used in connection with one type of press, it is obviously capable of use with other apparatus and I contemplate such modifications and changes as come within the scope of the appended claims.

I claim:

1. In a press, an impression roll, supports for said roll, a shaft for the roll, a driven gear loosely fitted on said shaft, means carried by the shaft adapted to operatively connect the gear to the shaft, and means adapted to engage the roll to lock it against rotation.
2. In a press, an impression roll, supports for said roll, a shaft for the roll, a driven gear loosely fitted on said shaft, means carried by the shaft adapted to operatively connect the gear to the shaft, and a link pivoted to a support and adapted to engage the roll to lock it against rotation.

Signed at Washington, D. C., this 23rd day of August, 1923.

SAMUEL ELDER.
